DISPENSER FOR PLASTIC FILM WRAP

Gerard Jamois, Nogent-sur-Marne, and Sylvain Bluntz,
Paris, France, assignors to Colgate-Palmolive Company,
New York, N.Y.

Filed July 12, 1973, Ser. No. 378,742

Claims priority, application France Feb. 9, 1973

Term of patent 14 years

Int. Cl. D20—02

U.S. Cl. D52—2 C

FIG. 3

FIG. 2

FIG. 4

FIG. 5

FIG. 1 is a top, left perspective view of a dispenser for plastic film wrap showing our new design in a partially opened position;

FIG. 2 is a front elevational view thereof in the closed position;

FIG. 3 is a left side elevational view thereof, the right side being a mirror image thereto;

FIG. 4 is a rear elevational view of FIG. 2;

FIG. 5 is a bottom plan view of FIG. 2.

We claim:

The ornamental design for a dispenser for plastic film wrap, as shown and described.
